UNITED STATES PATENT OFFICE.

WILLIAM CHAPMAN, OF MESABA, MINNESOTA.

POISON-BOTTLE.

1,086,995.

Specification of Letters Patent. Patented Feb. 10, 1914.

Application filed April 26, 1913. Serial No. 763,878.

To all whom it may concern:

Be it known that I, WILLIAM CHAPMAN, a citizen of the United States, residing at Mesaba, in the county of St. Louis and State 5 of Minnesota, have invented new and useful Improvements in Poison-Bottles, of which the following is a specification.

This invention relates to poison bottles; and it has for its primary object the provision 10 of a stopper therefor and means for mounting the same for unusual withdrawing movements upon the neck of the bottle, so that the user will have his attention directed to the indicating surface of the stopper and 15 thereby necessitate his becoming acquainted with the nature of the bottle's contents during the operation of effecting a release of the stopper.

Another object of the invention is the 20 provision of a device of this character wherein the stopper may be quickly removed by one acquainted with this construction.

With these and other objects in view, the invention consists of certain novel features 25 of construction, combination and arrangement of parts, as will be hereinafter described and claimed.

In the accompanying drawings Figure 1 is a perspective view of the bottle; Fig. 2 is a 30 vertical section therethrough; Fig. 3 is a similar view, showing the locking member in a partly released position; and Fig. 4 is a section on line 4—4 of Fig. 3.

The bottle 1 has its neck 2 terminating in 35 an upper annular flange 3 wherein vertical grooves 4 are formed at diametrically opposite points the upper ends of the grooves opening directly onto the upper surface of the flange, while the opposite ends of the 40 grooves open directly onto the lower retaining surface 5.

The stopper 6 is provided with a plug portion 7 of a configuration conforming with the internal shape of the neck 2 of the bottle, the lower end of the plug being closed 45 as at 8, while the upper end is provided with an annular flange 9 having vertical parallel grooves 10 therein at diametrically opposite points which open through horizontal branches 11 into a vertical bore 12 of the stopper. The bore 12 is cylindrical in transverse section and is designed to receive a correspondingly formed intermediate portion 13 of a vertically movable locking device 14. The device 14 is provided 50 with radial branches 15, which extend from

the intermediate portion 13, and as illustrated said branches are designed for vertical movements in the horizontal branches 11 of the grooves 10. The branches 15 are provided with depending vertical legs 16 which terminate in inwardly extending lugs 17. The lugs 17 are spaced for a distance slightly greater than the diameter of the flange 9 at 60 points in line with or through the grooves 10, whereby they may be freely moved vertically in the grooves, as will be understood.

The intermediate portion 13 of the securing member has fixed thereto one end of a coiled spring 18, said spring being extended 65 into the bore 12 and having its opposite end seated against the closed end of the bore, whereby the spring normally exerts its force to hold the securing member under tension. In applying the stopper to the bottle neck, 70 the portion 13 of the securing member is depressed manually so as to bring the branches 15 into the horizontal branches 11 of the grooves 10. The stopper is then adjusted over the neck of the bottle, so as to bring 75 the lugs 17 into registration with the vertical peripheral grooves 4 in the flange 3. Vertical pressure in a downward direction is then applied to the stopper and to the securing member until the flange 9 of the 80 stopper rests against the flange 3 of the bottle neck. The stopper is then rotated with a continuous application of pressure of the hand of the operator against the portion 13 of the securing member so as to permit the 85 stopper to be moved with freedom and the lugs 17 of the securing member adjusted to underlie the surface 5 of the flange 3 at points remote from the grooves 4. The stopper is then in its applied position and to remove the same from the bottle, the movements hereinbefore described must be 90 reversed until the lugs 17 of the securing member of the stopper are alined with the vertical grooves 4 in the bottle neck. The 95 flange 9 is provided on its upper surface with indicating matter, such as the words "Beware" and "Poison." While the intermediate portion 13 has printed or otherwise suitably formed thereon the word "Of" 100 which when connected with the previously described words forms such information as will disclose to the user of the bottle that the contents thereof is in the form of a poisonous drug. The unusual method necessary to 105 the release of the stopper from the bottle constantly directs the attention of the opera-

tor to the indicating matter on the surface of the stopper, as is obvious. It is desirable that the spring 18 under its force holds the lugs 17 engaged with the surface 5 with such friction that the operation of revolving the plug without simultaneously depressing the portion 13 of the securing member is rendered extremely difficult, if not impossible.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as claimed.

Having thus described my invention, what I claim is:—

A poison bottle having its neck provided with an annular flange, said flange having diametrically disposed vertical grooves, a

stopper removably fitting in the neck and provided with an upper annular flange co-extensive with the flange of the neck, said stopper having a vertical bore, a locking member removably mounted on the stopper and provided with depending vertical legs terminating in horizontal lugs, the said lugs being insertible through the groove in the flange of the neck, the stopper being mounted for rotation in the neck whereby to permit the lugs of said member to engage against the flange of the neck, and a spring carried by the member and extending through the bore of the stopper and exerting its tension against the member so as to eject the member when the lugs of the latter are aligned with said grooves.

In testimony whereof I affix my signature in presence of two witnesses.

WILLIAM CHAPMAN.
